UNITED STATES PATENT OFFICE

159,973

BUG DEFLECTING HOOD ORNAMENT

Michael T. Foley, Madison, Wis.

Application February 27, 1950, Serial No. 8,169

Term of patent 7 years

(Cl. D14—18)

To all whom it may concern:

Be it known that I, Michael T. Foley, a citizen of the United States, residing at Madison, in the county of Dane and State of Wisconsin, have invented a new, original, and ornamental Design for Bug Deflecting Hood Ornament, of which the following is a description, reference being had to the accompanying drawing, forming a part thereof.

In the drawing:

Fig. 1 is a top perspective view of a bug deflecting hood ornament embodying my new design;

Fig. 2 is a side view of the bug deflecting hood ornament; and

Fig. 3 is a somewhat reduced front view thereof.

I claim:

The ornamental design for a bug deflecting hood ornament, substantially as shown.

MICHAEL T. FOLEY.
